Primary Examiner — Cynthia Underwood(74) *Attorney, Agent, or Firm* — Lorenz & Kopf LLP(57) **CLAIM**

The ornamental design for a shake-proof hook, as shown and described.

DESCRIPTION

FIG. 1 is a front perspective view of the shake-proof hook in accordance with an exemplary embodiment;

FIG. 2 is a rear perspective view of the shake-proof hook, the rear perspective view opposing the front perspective view of FIG. 1;

FIG. 3 is a top view of the shake-proof hook of FIG. 1; FIG. 4 is a first side view of the shake-proof hook of FIG. 1;

FIG. 5 is a first end view of the shake-proof hook of FIG. 1; FIG. 6 is a second end view of the shake-proof hook, the second end view opposing the first end view of FIG. 5; FIG. 7 is a second side view of the shake-proof hook, the second side view opposing the first side view of FIG. 4; and, FIG. 8 is a bottom view of the shake-proof hook, the bottom view opposing the top view of FIG. 3.
